UNITED STATES PATENT OFFICE.

LEVIN J. HYSLUP, OF KELLER, VIRGINIA.

BALLOT-BOX.

1,211,854.

Specification of Letters Patent.

Patented Jan. 9, 1917.

Application filed January 8, 1916. Serial No. 71,052.

To all whom it may concern:

Be it known that I, LEVIN J. HYSLUP, a citizen of the United States, residing at Keller, in the county of Accomac and State 5 of Virginia, have invented certain new and useful Improvements in Ballot-Boxes; and I do hereby declare the following to be a full, clear, and exact description of the invention, such as will enable others skilled 10 in the art to which it appertains to make and use the same.

This invention relates to a ballot box to be used at various kinds of elections and the primary object of the invention is to provide 15 a ballot box which is constructed so that the ballot deposited within the box cannot be tampered with or changed without mutilating the ballot box in such a way that detection is readily achieved.

20 A further object of this invention is to provide a ballot box as specified which has a removable lid or cover, and to provide fabric sealing members which extend across the cover of the box and are sealed to the ends 25 of the box so that the cover cannot be removed from the box except by the cutting or breaking of the seals or fabric strips, and further to position a strip of fabric over the slot formed in the cover through 30 which the ballots are deposited into the box, so that ballots cannot be deposited into the box prior to the desired time.

With the foregoing and other objects in view, this invention consists in such novel 35 features of construction, combination and arrangement of parts as will be hereinafter more fully described, illustrated in the accompanying drawings and claimed.

40 In describing the invention in detail reference will be had to the accompanying drawings wherein like characters designate like and corresponding parts throughout the several views, and in which:

Figure 1 is a perspective view of the improved ballot box. Fig. 2 is a sectional view 45 on line 2—2 of Fig. 1. Fig. 3 is a sectional view on the line 3—3 of Fig. 2, and Fig. 4 is a section on the line 4—4 of Fig. 3.

Referring more particularly to the drawings, 50 1 designates the ballot box as an entirety which has ends 2 and 3 and a removable cover 4. The cover 4 may be either a hinged or slidably supported cover as desired. The ends 2 and 3 of the ballot box 1 are provided with a plurality of slots 5 extending therethrough, through which slots

the ends 6 of fabric strips 7 extend as clearly shown in Figs. 2 and 3 of the drawings. The strips 7 extend upwardly along the ends of the box and longitudinally over 60 the top of the cover 4. A sealing material indicated at 8 is attached to the outer surfaces of the ends 2 and 3 and engages the ends of the fabric strips for securely attaching the strips of fabric to the box. Certain portions of the sealing wax will enter 65 the slot 5 which will form anchors for the sealing wax or material. The strips 7 have their facing edges spaced as is shown at 9, for positioning upon the opposite sides of the 70 ballot depositing slot or opening 10 which is formed in the cover 4 of the ballot box 1. A fabric strip 11 is secured to the strip 7 and extends transversely thereto and over the outer opening of the slot 10.

When it is desired to use the ballot box at an election, the fabric strip 11 is cut so as to permit of the depositing of ballots through the slot or opening 10 into the box. After the election, the fabric strips 7 must 80 be cut and folded back off the cover to permit of the removal of the cover from the box, thereby preventing the fraudulent tampering with the ballots contained within the box owing to the fact that the opening of 85 the box cannot be accomplished without the mutilation of the fabric strips 7.

In reducing the invention to practice, certain minor features of construction, combination and arrangement of parts may be 90 altered to suit practical conditions provided such alterations are comprehended within the scope of what is claimed.

What is claimed is:

1. In a ballot box structure, the combination of a ballot box body having ends, a removable cover for said box, said cover being provided with a slot to permit of the insertion of ballots within the box, a fabric strip, a sealing material for attaching the ends of 95 said fabric strip to the ends of said ballot box, said fabric strip extending over the removable cover for preventing removal of the cover from the box, and a second fabric strip extending transversely across the cover 100 and secured to said first named fabric strip, said second named fabric strip extending over said slot.

2. In a ballot box structure, the combination, of a ballot box body including ends 110 and a removable cover, said ends being provided with a plurality of slots, a plurality of

fabric strips, the ends of said strips being inserted through said slots, said strips extending longitudinally across said removable cover, a sealing material attached to the 5 outer surfaces of the end of said box and engaging the ends of said fabric strips for securely sealing the fabric strips in place for preventing the removal of said cover.

3. In a ballot box structure, the combination of a ballot box body including ends and 10 a removable cover, said ends being provided with a plurality of slots, a plurality of fabric strips, the ends of said strips being inserted through said slots, said strips extending longitudinally across said removable 15 cover, a sealing material attached to the

outer surfaces of the ends of said box and engaging the ends of said fabric strips for securely sealing the fabric strips in place for preventing the removal of said cover, 20 said cover being provided with a slot for permitting of the deposit of ballots within said ballot box, and a fabric strip secured to said first named fabric strips and extending over said slot.

25

In testimony whereof I affix my signature in presence of two witnesses.

LEVIN J. HYSLUP.
